(57) **CLAIM**

The ornamental design for a receptacle, as shown and described.

DESCRIPTION

FIG. 1 is a perspective view of a receptacle showing our new design;

FIG. 2 is another perspective view thereof;

FIG. 3 is a front elevation view thereof;

FIG. 4 is a rear elevation view thereof;

FIG. 5 is a left side elevation view thereof, the right side being a mirror image;

FIG. 6 is a top plan view thereof;

FIG. 7 is a bottom plan view thereof; and,

FIG. 8 is a left side elevation cross-section view thereof taken along line 8—8 of FIG. 3.

The broken lines immediately adjacent shaded areas represent bounds of the claimed design and environment while all other broken lines are directed to environment and are for illustrative purposes only. The broken lines form no part of the claimed design.
